BARREL COVER LOCKING MEANS

Frederick Mauer, Matawan, N. J.

Application May 10, 1947; Serial No. 747,243

5 Claims. (Cl. 217—89)

1

This invention relates to improvements in closures for receptacles, such as, for example, cylindrical boxes, barrels and the like, and it relates particularly to improvements in closures which may be detachably secured to such containers.

An object of the invention is to provide a closure in the form of a lid or head which can be clamped securely on the end of a receptacle and can be released readily to permit removal of the closure from the receptacle.

A further object of the invention is to provide a detachable closure for receptacles including a locking mechanism supported on and forming a part of the closure in which the locking mechanism is protected against inadvertent release.

Other objects of the invention will become apparent from the following description of a typical form of closure embodying the present invention.

In accordance with the present invention, I have provided a closure for circular or cylindrical receptacles, such as barrels, tubs, boxes, cans, jars and the like, in which the closure is provided with a depending flange adapted to engage around the end of the receptacle, this flange being compressible and supporting a split band which may be compressed to force the flange into tight frictional locking engagement with the end of the receptacle.

More particularly, the flange of the closure member is provided with a plurality of slits which divide it into a plurality of relatively movable segments. The split band fits around these segments so that when the band is contracted, the segments are deflected, and compressed against the sides of the receptacle.

The means for compressing the band consists of a lever member which is supported on a pivot carried by one of the segments of the flange. This lever is provided with suitable camming means cooperating with the ends of the split band so that when the lever is moved downwardly into substantially parallel relationship with the flange, the band is contracted to compress the segments against the sides of the receptacle.

The flange preferably is provided with a rolled or beaded lower edge, this bead being provided with a slot for receiving an offset or laterally directed projection on the lever so that the lever is retained in parallelism with the flange and is disposed largely within the perimeter of the bead. The end of the laterally directed portion may be provided with an aperture for securing means, such as a twisted wire, to prevent the lever from being swung inadvertently into a position where-

in the closure is released from the receptacle.

For a better understanding of the present invention, reference may be had to the accompanying drawing, in which:

5. Figure 1 is a view in side elevation of a typical form of closure embodying the present invention as applied to a receptacle shown partly broken away;

Figure 2 is a view in section taken on line 2—2 of Figure 1; and

Figure 3 is a view in section taken on line 3—3 of Figure 1.

The invention will be described hereinafter in connection with a generally cylindrical receptacle 10 which may take the form of a fiber barrel of a type well-known in the art. Receptacles of this type are commonly used for packaging powders and other materials, and, therefore, to prevent leakage, it is desirable to provide a head or end closure for the barrel which can be secured tightly to the barrel in sealing relation.

The closure or head for the barrel embodying the present invention may consist of a circular member 11 having a depending flange 12 which is provided with a rolled beaded edge 13. As illustrated, the center portion of the closure is flat. However, if desired, it may be provided with suitable corrugations to strengthen it and to engage against suitable shoulders formed within the container, not shown.

The flange 12 of the closure is provided with a plurality of transversely extending slits or slots 14 which render the flange flexible so that the segments between the slots can be compressed against the side of the container 10.

In order to form a firm support for the closure, the upper edge or lip of the barrel 10 may be reinforced by means of a channel-like bead 15 which is compressed against the lip of the barrel, and has its inner edges 16 and 17 clinched into the barrel. This bead may be provided with a sealing gasket, not shown, at its outer edge for sealing engagement with the inner surface of the closure. Alternately, the closure may be provided with such a sealing gasket for engagement with the outer edge of the bead 15.

The closure may be secured firmly and tightly to the lip of the container by means of a split clamping band 18 which extends around the flange 12 and has its opposite inner ends 20 and 21 disposed on opposite sides of a pin 22 which is secured in the flange 12 by riveting, welding or in any other desired way. The inner ends 20 and 21 of the split band are also provided with headed pins 23 and 24 which are welded or riveted to

the ends of the bands. These rivets 23 and 24 engage in spiral cam slots 25 and 26 respectively in the base or inner end 27 of a lever 28 which is pivotally mounted on the pin 22. The inclination or curvature of the slots 25 and 26 is such that when the lever 28 is in the dotted line position shown in Figure 1, the band is expanded so that the flange segments 12 can spring outwardly and thus permit the closure to be detached from the end of the barrel 10. When the lever 28 is swung downwardly to the full line position shown in Figure 1, the ends 20 and 21 of the band are drawn closer together so that the band 19 compresses the flange 12 into the undercut portion 13 of the rim 15 of the barrel and thereby locks the closure tightly to the end of the barrel 10.

The lever 28 is provided with a downwardly or laterally directed end portion 29 which is adapted to pass through a slot 30 in the beaded rim 13, as shown in Figure 1, to prevent the lever from being sprung outwardly away from the closure if it should catch on something as the barrel is being filled or otherwise handled. The lever can be locked so that the closure cannot be released inadvertently by providing a hole 31 in the end of the lever for receiving a twisted wire 32 or other locking member.

The band 19 is not readily released from the closure when it has been attached thereto, for it cannot drop downwardly due to the presence of the beaded lower edge of the flange. Upward movement of the band 19 can also be prevented by means of suitable protuberances 33 disposed around the circumference of the flange. One protuberance 33, near the end 20 of the band 19, also prevents the end 20 of the band from being moved upwardly as the lever 28 is moved in a clockwise direction into its clamping position.

From the preceding description of a typical form of closure member embodying the present invention, it will be understood that I have provided means for securely attaching a closure member to a container, and one in which the parts lie substantially flush with and within the perimeter or circumference of the closure member so that it will not be damaged or sprung by contact with other adjacent articles. Moreover, I have provided a very simple means for retaining the closure member in locked or clamped position so that it cannot be released inadvertently. Moreover, by the use of fixed pivot for the lever and a band which has both ends movable relatively to the pivot, a more uniform clamping pressure can be obtained around the circumference of the closure member than with the devices of the type produced heretofore.

It will be understood further that closures of the type described above can be made in many different sizes and designs and may be used with small or large receptacles as the purpose demands. Therefore, it will be understood that the form of the invention described above is illustrative and not to be considered as limiting the scope of the following claims.

I claim:

1. A closure for a receptacle comprising a circular head member having a depending flange, slits in said flange for rendering it flexible, a split band encircling said flange, said band having adjacent ends, a lever pivotally mounted on said flange for movement in a plane substantially tangential to said flange, and camming means connecting said lever to said opposite ends of said

band for compressing said band around said flange upon pivotal movement of said lever in one direction.

5 2. A closure for a receptacle comprising a circular head member having a depending flange, slits in said flange for rendering it flexible, a split band encircling said flange, said band having adjacent ends, a pin fixed to and extending substantially radially outwardly from said flange between said adjacent ends of said band, a lever pivotally mounted on said pin, and camming means connecting said lever to said adjacent ends of said band for compressing said band against said flange and flexing the latter into engagement with said receptacle.

10 3. A closure for a receptacle comprising a circular head member having a depending flange, slits in said flange for rendering it flexible, a split band encircling said flange, said band having adjacent relatively movable ends, a pin fixed to and extending outwardly from said flange between said adjacent ends, a lever pivotally mounted on said pin, substantially spiral cam slots in said 15 lever on opposite sides of said pin, and means on the adjacent ends of said band engaging in said slots, whereby pivotal movement of said lever in opposite directions compresses and expands said band relatively to said flange.

20 4. A closure for a receptacle comprising a substantially circular cover member having a depending flange, a rolled edge on said flange, slits extending at least partially across said flange dividing it into a plurality of relatively movable, flexible segments, a pin fixed to and extending radially from said flange, a lever mounted for rotary movement on said pin, a split band encircling said flange and having relatively movable adjacent ends on opposite sides of said pin, and camming means connecting said adjacent ends to 25 said lever to compress said band around said flange upon movement of said lever toward said rolled edge.

30 5. A closure for a receptacle comprising substantially circular cover member having a depending flange, a rolled edge on said flange, slits extending at least partially across said flange dividing it into a plurality of relatively movable, flexible segments, a pin fixed to and extending radially from said flange, a lever mounted for 35 rotary movement on said pin, a split band encircling said flange and having adjacent, relatively movable ends on opposite sides of said pin, camming means connecting the ends of said band to 40 said lever to expand and contract said band upon movement of said lever away from and toward said rolled edge, respectively, a slot in said rolled edge, and a projection on the outer end of said lever engageable in said slot when said band is contracted.

60 6. FREDERICK MAUER.
